UNITED STATES PATENT OFFICE.

WILLIAM E. SCHNEIDER, OF WASHINGTON, DISTRICT OF COLUMBIA.

DESIGN FOR A VEHICLE-BODY.

SPECIFICATION forming part of Design No. 32,368, dated March 20, 1900.

Application filed February 20, 1900. Serial No. 5,973. Term of patent 14 years.

To all whom it may concern:

Be it known that I, WILLIAM E. SCHNEIDER, a citizen of the United States, residing at Washington, District of Columbia, have invented and produced a new and original Design for Vehicle-Bodies, of which the following is a specification.

In the accompanying drawings, forming a part thereof, Figure 1 is a side elevation, Fig. 2 is a front end elevation, and Fig. 3 is a rear end elevation.

The essential features of my new and original design comprise a vehicle-body of rectangular form, having a front extension-platform, an overhanging top projection, a downward rear extension, and recesses at the lower side portions.

Thus A represents the body of the vehicle, of a general rectangular form, longer than

its width or height, and there is a platform 20 extension B at the front of the vehicle, with an upward projection C, and overhanging the extension there is a top projection D. At the rear end of the body there is a downward extension E, and the lower parts of the sides of 25 the body are recessed at F and have curved flanges G.

What I claim is—

The design for a vehicle-body, substantially as herein shown and described.

In testimony whereof I have signed my name to this specification in the presence of 30 two subscribing witnesses.

WILLIAM E. SCHNEIDER.
